UNITED STATES PATENT OFFICE

LOUIS LA BRANCH, OF DAYTON, OHIO

OIL BURNER

Application filed October 6, 1927. Serial No. 224,388.

My invention relates to hydro-carbon fuel burners of the vapor generator type wherein the fuel, preferably oil, is vaporized by being pre-heated and the vapors subsequently 5 mixed with air to form a combustible mixture. The present construction is a further development and amplification of that disclosed in co-pending application, Serial No. 41,842, filed July 6, 1925. In the present 10 invention there is contemplated a dome shape shaped mixing chamber surmounted by a vaporizing chamber in which the vaporizing liquid fuel is conducted. The top of the dome shaped mixing chamber is 15 perforated, and a series of air ducts or nozzles project within the mixing chamber from the bottom thereof into proximity with the vent openings in the top to supply air for intermixture with the vapors supplied to such 20 mixing chamber from the superposed vaporizing chamber. Externally surrounding the dome shaped burner chamber is an independent series of air inlet ducts and also 25 an annular tuyère discharging downwardly at the base of the dome shaped burner chamber. The interior and exterior air supply ports or ducts including the annular tuyère are independently supplied with air so that 30 the air supply interiorly and exteriorly of the burner chamber may be regulated or relatively proportioned. An annular gutter surrounds the burner chamber exteriorly 35 thereof serving as a drainage channel for excess and unvaporized fuel and also as a distributing channel for a priming charge to facilitate initiation of the burner operation. Connected with this channel is a 40 priming chamber or initial vaporizer equipped with an electric heater by which the preliminary priming charge may be vaporized and associated therewith is a spark plug or other ignition means by which the preliminarily generated vapors may be 45 ignited.

The object of the invention is to simplify the structure as well as the means and mode of operation of such hydro-carbon fuel burners, whereby they will not only be cheapened 50 in construction, but will be more efficient in

operation, automatic in action, easily controlled and unlikely to get out of repair.

A further object of the invention is to provide a burner in which the fuel will be thoroughly consumed leaving a minimum of 55 soot and residue.

A further object of the invention is to provide in such a burner an improved form of air distribution and control, whereby air is not only supplied interiorly of the burner 60 compartment for intermixture with the vaporized fuel, but an additional air supply is provided exteriorly of the burner compartment to insure free, full and complete fuel consumption. 65

A further object of the invention is to provide improved means for priming or initially operating such burner to induce automatic generation.

A further object of the invention is to 70 provide improved burner constructions and arrangement of parts whereby they will be free to compensate for expansion and contraction.

With the above primary and other incidental objects in view, as will more fully appear in the specification, the invention consists of the features of construction, the parts and combinations thereof, and the mode of operation, or their equivalents, as 75 80 hereinafter described and set forth in the claims.

Referring to the accompanying drawings, Fig. 1 is a vertical sectional view of the assembled mechanism forming the subject 85 matter hereof. Fig. 2 is a top plan view partly broken away of the assembled burner illustrated in Fig. 1. Fig. 3 is a side elevation partly broken away of a hot air furnace to which the present burner has been applied. 90

Like parts are indicated by similar characters of reference throughout the several views.

While the present burner is especially designed for domestic use in furnaces and stoves, it is not limited to such use but may be applied to industrial purposes in any installation wherein an automatic generating liquid burner is desirable. 95

Referring to the drawings the burner embodies a base member 1 having a marginal upstanding flange 2 and in inwardly spaced relation therewith a second upstanding wall 5 or flange 3. Intermediate the marginal flange 2 and concentric wall 3 there is formed an annular channel 4 which serves both as a drainage channel for condensed or unvaporized fuel and also as a distributing channel for a priming charge. The concentric inwardly spaced wall 3 is formed with an offset or step 5 through which extend a plurality of vertically disposed air inlet conduits or ports 6, extending entirely through 10 the unit or base member 1. Internally of the concentric wall 3 the bottom or base member 1 is preferably, though not necessarily, of concavo-convex form, the upper or convex side of which is provided with a plurality 15 of spaced upstanding air supply nozzles or conduits 7-7. These nozzles 7 open at their lower ends into a compartment 8 beneath the unit or base member 1 formed by a dependent flange 9. Superposed upon the base member 1 is a concavo-convex cover section 20 10 having therein a multiplicity of vent openings or perforations 11 through which the combustible mixture of fuel vapors and air is released and burned. The margins 25 of this concavo-convex cover section rest upon the beveled top margin of the wall 3. The beveled or inclined engagement of the cover section 10 upon the upper margins of such wall 3 is free to permit relative expansion and contraction of the cover section 10 in relation with the base unit. This cover section 10 is centrally provided with a concentric dependent tapered flange 12 extending into close proximity to the bottom of the base unit 1. This dependent tapered flange 40 25 affords within the burner chamber a concentric distributing compartment 13 for fuel vapors which are fed to the mixing chamber 14 of the burner through the intervening space beneath the lower margin of the concentric flange 12. The distributing chamber 13 communicates with the combustion chamber 14 only through its bottom and well below the top of the air inlet or jet nozzles 7. Thus the fuel supply admitted 45 30 to the combustion chamber 14 from the distributing chamber 13 must necessarily pass upwardly from the lower margin of the flange 12 through the body of air supplied by the inlet or jet nozzles 7 to the vent perforations 11. This insures a thorough and uniform intermixture of fuel vapors and air into a uniformly combustible mixture.

Seated within a recess or pocket formed 50 55 in the convex or cover section 10 of the burner is an inverted bell shaped vaporizing chamber 15. This vaporizing chamber 15 has a centrally disposed dependent spud 16 which extends through a central hub 17 of the base or bottom unit 1, and connects with

a fuel supply conduit 18. The liquid fuel entering the burner through the supply conduit 18 and the hollow stem or inlet spud 16 is subjected to the heat of combustion of the vaporized and carbureted gas or vapors being burned over the top surface of the convex cover section 10 entirely surrounding the vaporizing chamber 15. The vapors arising within the chamber 15 from such heated liquid fuel escape downwardly 70 75 through the upstanding conduit 19 which projects within the chamber 15, and communicates at the lower end with the distribution compartment 13 of the burner. Merely as a safety outlet in the event of an excess pressure of vaporized fuel accumulating within the chamber 13 there is provided in the top thereof a safety valve which may be of any suitable form. In the present instance there is shown a conventional form 80 85 of safety outlet comprising a ball valve 20 closing a relief vent 21 and loosely held against bodily displacement but permitting ample movement to relieve pressure in the chamber by a retaining chamber 22. This conventional form of safety relief valve is shown for illustrative purposes only and it is to be understood that any other form of relief valve may be utilized. A drain pipe 25 communicates through an outlet opening 26 with the interior of the burner chamber 14 at one side thereof, and at the same time communicates with an overflow well 27 which takes the place of one of the air inlet ports 6, but terminates at a lower level. 90 95 Any excess liquid fuel accumulating in the channel 4 would overflow such drain well 27 passing thence through the outlet 26 into the drain pipe 25. The top of the drain well 27 is located, however, at a level sufficiently above the bottom of the channel 4 to retain therein an ample priming charge of liquid fuel. Communicating with the bottom of the channel 4 is a primary vaporizing chamber 28 which is for temporary use only 100 105 in starting the burner in operation. This primary vaporizing chamber 28 contains an electrical heater unit 29 and is supplied with liquid fuel through a supply conduit 30. Sufficient fuel is admitted through the conduit 30 to fill the vaporizing chamber 28 and rise into the priming channel 4. A check valve 31 is preferably, though not necessarily, provided intermediate the initial vaporizing chamber 28 and the priming channel 110 115 120 125 130 4. The liquid fuel within the chamber 28 becoming heated, vapors will arise therefrom and from the liquid within the channel 4. Located immediately above the conduit connection between the initial vaporizer 28 and the valve 4 is an electrical ignition device, which in the present instance has been shown as the conventional form of spark plug 32. To prevent flashing or spluttering as the liquid fuel and vapors arise

from the initial vaporizing chamber 28 into the channel 4 a small baffle plate or bar 32 is provided above the inlet opening. As these vapors arise about the spark plug 32 they are ignited thereby, the ignition of such vapors in turn serving to ignite the liquid fuel within the channel 4 through which the flame follows throughout the periphery of the burner. The heat from such burning fuel serves to raise the temperature of the vaporizing chamber 15 to generating heat whereupon the automatic generation of fuel vapors is induced and the operation of the burner becomes automatic.

Surrounding the burner is a tuyère 34 discharging downwardly immediately above the channel 4 and outside the periphery of the combustion chamber. Air is supplied to the tuyère 34 through a ring 35 surrounding the peripheral flange 2 of the burner. The ring 35 is provided with an inwardly projecting flange 36 having in it a succession of spaced notches 37. Adjustably resting upon the flange 36 is a slidingly revoluble damper ring 38 having therein holes 39 which are moved into and out of registry with the notches 37 by the revoluble sliding adjustment of such damper ring. By this means the volume of air discharged through the tuyère 34 is regulated. The air supply exteriorly of the combustion chamber through the air port 6 and tuyère 34 is entirely independent of the air supply through the jet nozzles 7 within the combustion chamber. Referring to Fig. 3 as shown an air supply conduit 40 which may lead from any suitable source of air supply, preferably outside the building. This conduit 40 extends within the ash pit compartment of the furnace 41 and is connected at its inner end with the chamber 8 of the burner unit 1. The conduit 40 is provided with a regulating damper 42 by which the supply of air may be controlled. This air supply is thus conducted by the conduit 40 direct to the chamber 8 which communicates through the jet nozzles 7 with the interior of the combustion chamber 14. The separate air inlet 43 leads to a housing 44 connected with and closing the ash pit opening of the furnace 41. The conduit 40 before mentioned extends through the housing or air vent 43 without communicating therewith. The housing or shaft 43 communicates through the ash pit door with the interior of the furnace 41 beneath the burner. Air admitted to the ash pit space 44 rises through the supply ports 6 surrounding the burner and through the tuyère 34, the capacity of which is regulated by the slidable damper plate 38. To facilitate the assembly of the burner within the fire pot of the furnace 41 and enable the introduction of its parts through the firing door thereof, the ring 36 may be formed in separable sections as indicated in the plan view Fig. 2. The tuyère 34 may also be formed in semi-circular sections to be interconnected, although it is preferably made as a single part, the ordinary firing door being sufficiently large to admit this member. The overflow conduit 25 preferably, though not necessarily, discharges into a drip container 6 connected with a cutoff valve 47 in the supply conduit 18. The arrangement is such that whenever the overflow becomes excessive the waste of the accumulation in the drip pan will operate the valve 47 to shut off the fuel supply. Obviously this excess accumulation would only occur when the fire for some reason was accidentally extinguished while the fuel continued to flow.

While extensive trials have shown that a burner constructed as heretofore described will consume the fuel completely without the deposit of soot or residue if air is supplied in proper proportions. Means is provided for removing the soot and opening the vent holes 11 in the event that through misoperation, poor fuel or faulty combustion an accumulation of soot should occur within in the combustion compartment 14. To this end there is mounted on the under side of the concave cover portion 10 of the burner a sliding ring 48 having a series of radially disposed fingers 49 extending in close proximity to the under side of the cover section 10 and across the field of vent perforations 11. The ring 48 is connected with the cover section 9 by studs 50 projecting through arcuate blocks 51, which enable a limited sliding movement of the ring in a rotary direction. By thus shifting the ring to and fro within the limits determined by the slots 51 the fingers 49 may be made to dislodge any soot deposit on the interior of the cover section 10.

The burner is supported within the furnace 41 upon the ring 36 which rests upon the bottom of the fire pot. This ring 36 is provided at spaced intervals with inwardly projecting fingers 53 on which rest lugs 54 projecting from the outer face of the peripheral flange 2 of the burner unit 1.

From the above description it will be apparent that there is thus provided a device of the character described possessing the particular features of advantage before enumerated as desirable, but which obviously is susceptible of modification in its form, proportions, detail construction and arrangement of parts, without departing from the principle involved or sacrificing any of its advantages.

While in order to comply with the statute the invention has been described in language more or less specific as to structural features it is to be understood that the invention is not limited to the specific details shown, but that the means and construction herein dis-

closed comprises the preferred form of several modes of putting the invention into effect and the invention is, therefore, claimed in any of its forms or modifications within 5 the legitimate and valid scope of the appended claims.

Having thus described my invention, I claim:

1. In a burner of the character described, 10 a chamber comprising a base member having upstanding peripheral walls, a perforated dome for said chamber, the peripheral portion of which rests loosely upon the upstanding walls of the base member to permit 15 expansion and contraction, and centrally disposed means for positioning the perforated dome relative to said base, and means for supplying a combustible mixture of fuel and air to said chamber.
2. In a burner of the character described, 20 a chamber comprising a base member having upstanding beveled peripheral wall, a concavo-convex perforated dome the marginal portion of which rests upon the beveled edge of said wall, centrally disposed interconnections between the base and perforated dome and means for supplying a combustible mixture of fuel and air to said chamber.
3. In a burner of the character described, 25 a perforated dome, means for supplying vaporized fuel to the interior of said dome, an annular gutter about the base of said dome, means for supplying liquid fuel to said gutter for priming purposes, and means for preheating the priming fuel supplied to said gutter.
4. In a burner of the character described 30 a vaporizing chamber, a mixing chamber for gaseous fuel communicating with the vaporizing chamber and having a perforated top, air supply means leading to the interior of the mixing chamber through the bottom thereof, a hollow tuyère ring surrounding the mixing chamber and having a downwardly directed discharge opening contiguous to the periphery of the perforated mixing chamber and below the level of the 35 perforated top thereof and means for regulating the supply of air through said tuyere.
5. In a burner of the character described 40 a vaporizing chamber, a mixing chamber for gaseous fuel communicating therewith and having a perforated top through which the fuel is discharged for consumption, means for supplying air to the interior of said mixing chamber through the bottom thereof, a hollow upstanding wall extending above the 45 level of the perforated top of the mixing chamber and peripherally surrounding said mixing chamber, said hollow wall having a discharge opening adjacent to its bottom and below the level of the perforated top 50 of the mixing chamber and means for sup-

plying air to said hollow wall for discharge through said opening.

6. In a burner of the character described, 55 a vaporizing chamber, a receiving chamber for fuel having a perforated top, a gutter peripherally surrounding said fuel chamber, a tuyère comprising an upstanding wall extended inwardly and thence downwardly into overhanging relation with said gutter forming a circuitous air passage open at its 60 bottom contiguous to said channel, and means for supplying air in regulated quantity through said passage.

7. In a burner of the character described 65 a vaporizing chamber, a receiving chamber for gaseous fuel having a perforated top for the discharge of the fuel, and a concentric air chamber extending above the level of the perforated top of the fuel chamber and having a discharge opening below 70 the level of the perforations of said chamber, and an air supply to both said chambers.

8. In a burner of the character described, 75 the combination with a vaporizing chamber and a perforated gaseous fuel receiving chamber, of a circuitous air chamber surrounding the fuel chamber, said circuitous chamber being open at its bottom and discharging into proximity to the perforated area of said gaseous fuel receiving chamber, a septum dividing the circuitous chamber into inlet and outlet portions, and a regulating damper controlling the flow of air through said chamber to the perforated area of said fuel receiving chamber.

9. In a burner of the character described, 80 the combination with a vaporizing chamber and a perforated gaseous fuel receiving chamber, of a circuitous air chamber surrounding the fuel chamber, said air chamber being open at its bottom, a septum dividing the open bottom into inlet and outlet portions, and an apertured damper slidingly adjustable within said air chamber regulating the flow of air from the inlet to the outlet portions thereof.

10. In a burner of the character described, 85 the combination with a vaporizing chamber and a perforated gaseous fuel receiving chamber of an inverted channel shaped tuyère surrounding said perforated fuel receiving chamber, a septum dividing the open bottom of the inverted channel into intake and discharge orifices, said inverted channel extending above the level of the perforated chamber with its open bottom discharging contiguous to the periphery of the perforated fuel receiving chamber and below the level of the perforations thereof.

11. In a burner of the character described 90 a vaporizing chamber, a perforated receiving chamber for gaseous fuel, an air supply to said perforated fuel chamber a second air supply discharging exteriorly of said

perforated fuel chamber and contiguous to the periphery thereof, and means for independently regulating the respective air supplies.

5 12. In a burner of the character described a vaporizing chamber, a perforated receiving chamber for gaseous fuel, an air supply leading to said fuel chamber, a series of air supply ports located about the periphery 10 of said fuel chamber, an independent air supply means therefor, a tuyère surrounding the perforated fuel chamber and series of independent air ports, and means for supplying air to said tuyère independently of 15 the air supplied to said fuel chamber and to said series of ports.

13. The combination with a perforated receiving chamber for gaseous fuel, a gutter surrounding the chamber for priming fuel, 20 an auxiliary fuel supply chamber for liquid fuel communicating with said gutter, a heater in said supply chamber by which said fuel is preheated and fuel vapors generated, and an ignition device in proximity to the 25 opening from said chamber to the gutter.

14. The combination with a perforated chamber for gaseous fuel, a priming gutter surrounding the chamber, means for supplying priming fuel thereto, a drainage outlet 30 from said chamber for condensation, and an overflow outlet from said gutter to said drainage outlet.

In testimony whereof, I have hereunto set my hand this 6th day of September, A. D. 35 1927.

LOUIS LA BRANCH.
